US00D978533S

(12) **United States Design Patent** (10) Patent No.: **US D978,533 S**
Dai (45) Date of Patent: **** Feb. 21, 2023**

(54) **CONTAINER**

(71) Applicant: **ShenZhen YiHong Technology Co., LTD**, Guangdong (CN)
(72) Inventor: **Yi Dai**, ShenZhen (CN)
(73) Assignee: **ShenZhen YiHong Technology CO., LTD**, ShenZhen (CN)

(**) Term: **15 Years**

(21) Appl. No.: **29/842,904**

(22) Filed: **Jun. 16, 2022**

(51) LOC (14) Cl. **03-01**
(52) U.S. Cl.
USPC **D3/307**
CPC **B65D 43/0202** (2013.01)

(58) **Field of Classification Search**

USPC D3/303–309; D9/737, 756, 761, 414,
D9/423–425, 430–432, 456;
D7/553.1–555, 557, 601, 603
CPC B65D 43/0202; B65D 25/06; B65D

“Set of 4 Refrigerator Organizer Bins Pop Soda Can Dispenser Beverage Holder for Fridge, Freezer, Kitchen, Countertops, Cabinets—Clear Plastic Canned Food Pantry Storage Rack” Sold by “Home & Party”; First available on Mar. 28, 2019. Site visited on Jun. 16, 2022, with link below https://www.amazon.com/Refrigerator-Organizer-Dispenser-Beverage-Countertops/dp/B07Q8JKGN3/ref=sr_1_5?cid=2ZTA776AYEA5Y&keywords=can+container&qid=1655409716&sprefix=can+container%2Caps%2C123&sr=8-5.

Primary Examiner — Richard E Chilcot

(74) Attorney, Agent, or Firm — iPA & iPM

(57) **CLAIM**

The ornamental design for a container, as shown and described.

DESCRIPTION

FIG. 1 is a perspective view of a container showing my new design;

FIG. 2 is a perspective bottom view of the container;

FIG. 3 is a right side view thereof;

FIG. 4 is a left view thereof;

FIG. 5 is a back view thereof;

FIG. 6 is a front view thereof;

FIG. 7 is a top view thereof;

FIG. 8 is a bottom view thereof; and,

FIG. 9 is an enlarged perspective view of area 9 from FIG. 2.

Broken lines illustrate environmental elements and/or portions of the container that form no part of the claimed design.

1 Claim, 6 Drawing Sheets
